UNITED STATES PATENT OFFICE.

WILHELM FELLENBERG, OF CHARLOTTENBERG, GERMANY.

INCLOSED SAFETY DEVICE FOR FUSES FOR ELECTRICAL INSTALLATIONS.

Specification of Letters Patent.

Patented Feb. 27, 1906.

No. 813,546.

Application filed April 28, 1904. Serial No. 205,367.

To all whom it may concern:

Be it known that I, WILHELM FELLENBERG, a subject of the German Emperor, residing at Charlottenberg, in the Empire of Germany, have invented a certain new and useful Inclosed Safety Device for Fuses for Electrical Installations, of which the following is a specification.

The devices for insuring the proper action of the fuses of electric plants must be so constructed as to provide under all circumstances, even in the case of short-circuiting of powerful sources of energy and no matter what the potential or current strength, complete protection against fire, detonation, or explosion. Care must, however, be taken that they do not become heated more than is avoidable by wattless currents, and provision must be made by a suitable choice of the materials employed for conducting the heat away. The safety device must, however, be of such a character that it can be used in the open as well as in places where there is moisture without the latter being able to penetrate into the inside.

The essential feature of the safety device in question consists in the combination of some characteristics which are already known with others which are still new. To be able to produce a safety device which is really efficient against fire, detonation, or explosion, it is necessary to unite these essential features suitably adapted to correspond with the potential and strength of the current to be employed in one combination.

The essential features of such a combination are—

First. Separation of the fuses connected in parallel by partition-walls or by casings which completely surround them.

Second. The arrangement of the fuses either in the form of coils or in zigzag form, in order to produce sparking distances connected in series one behind the other and to extinguish the arc by the electromagnetic action of the current. If the fuses are arranged in coils, it is advantageous to have coils of an elliptic shape and to interpose an armature-core for the purpose of producing a magnetic blow-out, by which means the electromagnetic action of the current is still further increased.

Third. Pliable yielding walls of insulating, not easily inflammable materials—such, for

instance, as asbestos and the like—which are arranged opposite to the fuses or completely surround them.

Fourth. Outlets arranged within the closed casing above the places where the fuses are bent and filling up of all the hollow spaces by means of substances adapted for such a purpose—such, for instance, as emery, talc, or the like.

The safety device constructed in the manner just described is surrounded by an outside casing of porcelain, stoneware, or glass, by means of which the heat produced by the maximum charge can be conducted to the outside in a comparatively short time in such a manner that no moisture can penetrate into the interior.

The blowing out of the fuses without giving rise to fire, detonation, or explosion is insured by dividing the fuses as much as possible and arranging them in separate chambers or between partitions, by which means the separate arcs of the various fuses connected in parallel are prevented from uniting. By arranging the fuses either in the form of coils or in zigzag form spark distances connected in series one behind the other are produced in each fuse, which extend in a uniform manner over the whole space of the safety device, with the result that only a part of the fuse, and that at the point where it is bent, melts.

Any arc which may be formed is blown out by the electromagnetic action of the current, which is still further increased by the magnetic blow-out if an armature-core has been arranged in the inside of the coil.

The spreading of the flames is prevented by filling up all the hollow spaces of the device with a suitable material—for instance, with emery, talc, or the like. Consequently when the fuses blow out the pressure of the gas on each part of the device is reduced by the gas being spread uniformly throughout the whole interior space, and its explosive action is diminished by the increase of the inside space, which increase is due to the yielding of the pliable walls composed, as already stated, of insulating, not easily inflammable material, with the result that, provided the limits permissible in practice have not been transgressed, the safety device cannot burst and no flames can penetrate to the outside, neither is it possible to hear any loud detonation.

Figures 1 to 7 represent different forms of

carrying out the invention. In Figs. 1 to 3 are shown the longitudinal and transverse sections of such a safety device with the fuses arranged in coils. Figs. 4 and 5 illustrate a device the fuses of which are arranged zig-zag-like, while in Figs. 6 and 7 are shown sectional views of plug-fuses.

Referring to the drawings, *a* denotes the outside casing of the device composed of porcelain, stoneware, glass, or any other non-conducting, insulating, refractory material; *b*, the chambers, pipes, or partitions in which the fuses are placed; *c*, the fuses; *d*, the material for filling up the hollow spaces—such as powdered emery, talc, carbide of silica, or any similar substance; *e*, the junction-contacts; *f*, the wall or the mantle, consisting of elastic, expansible, not inflammable, insulating material—for instance, asbestos or any similar material which yields or expands under powerful pressure and may be furnished with grooves in order to still further increase its yielding tendency; *g*, a cover of porcelain, glass, or similar material, which is intended to protect the device against moisture; *h*, partition-walls for separating the fuses from each other; *i*, elliptically-shaped pieces through which the fuses, which are divided for the purpose of being arranged in coils, may pass. These pieces serve at the same time as partition-walls for the arcs. *k*, outlets at the points where the fuses are bent; *l*, iron bridges for connecting the fuses, being of a greater cross-section in order to prevent undue heating, (if the fuses are arranged in zigzag form such bridges may likewise be interposed in place of windings); *m*, insulated armature-cores, which may at the same time serve as bolts for holding the device in position; *n*, packing of the safety device; *o*, glass-wool or similar material for loosely filling up the spaces by which the capacity of the cavity surrounding the fuse is increased.

What I claim as my invention, and desire to secure by Letters Patent, is—

1. A safety device for fuses consisting in combination of fuse-wires, non-conductors upon which said wires are coiled and partitions between said wire coils substantially as described.

2. A safety device for fuses consisting in combination of fuse-wires connected in parallel non-conductors upon which said fuse-wires are coiled and partitions between said coils substantially as described.

3. A safety device for fuses consisting in combination of fuse-wires connected in parallel non-conductors upon which said fuse-wires are coiled, partition between said coils and an elastic yielding inclosure for said wires substantially as described.

4. A safety device for fuses consisting in combination of fuse-wires connected in parallel non-conductors upon which said fuse-wires are coiled, partition between said coils,

an elastic yielding inclosure for said wires and filling material within said inclosure, substantially as described.

5. A safety device for fuses consisting in combination of fuse-wires connected in parallel non-conductors upon which said fuse-wires are coiled, partition between said coils, and an elastic yielding inclosure for said wires, and a non-conducting casing inclosing the whole, substantially as described. 75

6. A safety device for fuses consisting in combination of fuse-wires connected in parallel non-conductors upon which said fuse-wires are coiled, partition between said coils, an elastic yielding inclosure for said wires, 80 and filling material within said inclosure, and a non-conducting casing inclosing the whole, substantially as described.

7. A safety device for fuses consisting in combination of fuse-wires, non-conductors 85 upon which said wires are coiled and partitions between said wire coils, and an armature-core within said fuse-wire coils, substantially as described.

8. A safety device for fuses consisting in 90 combination of fuse-wires connected in parallel non-conductors upon which said fuse-wires are coiled and partitions between said coils, and an armature-core within said fuse-wire coils, substantially as described. 95

9. A safety device for fuses, consisting in combination of fuse-wires, non-conductors produced in series with said wires, and partitions between said fuse-wires, and an armature-core upon which said fuse-wires are 100 mounted, substantially as described.

10. A safety device for fuses consisting in combination of fuse-wires, non-conductors upon which said wires are coiled and partitions between said wire coils, an elastic 105 yielding inclosure for said wires, and a casing inclosing the whole, substantially as described.

11. A safety-fuse consisting in combination of fuse-wires, non-conductors upon 110 which said wires are coiled said non-conductors being of elliptical form and partitions between said fuse-wires substantially as described.

12. A safety-fuse consisting in combination of fuse-wires, non-conductors upon 115 which said fuse-wires are coiled in series, partitions between the non-conductors conductors connecting the fuse-wires in series an inclosing casing divided longitudinally, said non-conductors being formed integral with the respective parts of said casing, bolts for connecting the respective parts of the casing together said bolts passing through said non-conductors upon which the fuse-wires are 120 coiled and serving as armature-cores, substantially as described.

13. A safety-fuse consisting in combination of fuse-wires, non-conductors upon 125 which said fuse-wires are coiled in series, par-

- titions between the non-conductors, conductors connecting the fuse-wires in series an inclosing casing divided longitudinally, said non-conductors and partitions being formed
5 integral with the respective parts of said casing, bolts for connecting the respective parts of the casing together said bolts passing through said non-conductors upon which the fuse-wires are coiled and serving as armature-
10 cores and spaces within said casing between said partitions, yielding elastic inclosures within said spaces and filling material within said yielding elastic inclosures, substantially as described.
15 14. A safety-fuse consisting in combination of fuse-wires, non-conductors upon which said fuse-wires are coiled in series, partitions between the non-conductors, conductors connecting the fuse-wires in series, an inclosing
20 casing divided longitudinally, said non-conductors and partitions being formed

integral with the respective parts of said casing, partitions upon said non-conductors between which said fuse-wires are arranged in series, bolts for connecting the respective 25 parts of the casing together said bolts passing through said non-conductors upon which the fuse-wires are coiled and serving as armature-wires, substantially as described.

15. A safety device for fuses consisting in 30 combination of fuse-wires, non-conductors upon which said wires are coiled and partitions between said wire coils and an inclosing casing therefor and outlets therefrom, substantially as described.

35

In testimony whereof I have signed my name to this specification in the presence of two subscribing witnesses.
